US0D1048416S

(12) **United States Design Patent** (10) Patent No.: **US D1,048,416 S**
(45) Date of Patent: ** Oct. 22, 2024

(54) **HAND REHABILITATION DEVICE**

(71) Applicant: **Wenzhou Weinishi Intelligent Technology Co., Ltd**, Wenzhou (CN)

(72) Inventor: **Qixing Lin**, Wenzhou (CN)

(73) Assignee: **WENZHOU WEINISHI INTELLIGENT TECHNOLOGY CO., LTD.**, Wenzhou (CN)

(**) Term: **15 Years**

(21) Appl. No.: **29/934,739**

(22) Filed: **Mar. 27, 2024**

(51) LOC (14) Cl. **24-01**

(52) U.S. Cl.

USPC **D24/200**

(57) **CLAIM**

The ornamental design for a hand rehabilitation device, as shown and described.

DESCRIPTION

FIG. 1 is a front perspective view of a hand rehabilitation device, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the hand rehabilitation device, which form no part of the claimed design.

1 Claim, 8 Drawing Sheets
